GEORGE B. MEURER, OF FLUSHING, NEW YORK.

METAL SHINGLE.

Application filed February 20, 1923. Serial No. 620,183.

While the commercial use of metal shingles is increasing rapidly there are certain inherent deficiencies which prevent their use with the freedom in laying afforded by wooden shingles. Two fundamental attributes of satisfactory shingling should be provided for, to wit, a perfectly flat surface for all shingles in a row and flexibility in the order of laying successive rows and tiers without any interference in nailing. Metal shingles heretofore known have satisfied many of the requirements such as watertightness in the joints and butt edges for tightness but it has not been possible to lay the shingles in any desired relationship and insure juxtaposed shingles presenting a continuous uniform flat surface undisturbed by the joint line. Further, such shingles have presented the difficulty in nailing of overlapping strips and subsequent deformation from nailing.

It is the principal object of the present invention to provide a metal shingle which shall embody all of the advantages of known shingles and satisfy all ordinary requirements and shall, in addition, possess certain distinct improvements which facilitates the laying of the shingles rapidly in any desired relationship and their spacing and nailing without injury or deformation and without destroying the continuous flat level surface provided by shingles in any given row. In accordance with the invention it is proposed to provide the improved shingles with a tongue along one edge adapted to interengage with a groove along the other edge of a proximate shingle, and a nailing strip at the other end of peculiar form and disposition. This nailing strip is of such length and shape as to provide a shoulder which is engaged with the upper edge of the shingle in the next lower tier and thereby automatically position the shingle being laid without, however, permitting the nailing strip to overlie the shingle in the next lower tier. The effect produced is to greatly facilitate the laying of the shingles and their proper spacing with respect to one another and, of greatest importance, to permit the nailing of each shingle without nailing through any other shingle and thereby deforming it or changing the general level of the surface line of the shingles.

The invention will be described with greater particularity hereinafter with reference to the detailed description of the illus-

trated embodiment shown in the drawings, wherein:

Figure 1 is a view in plan of a metal shingle embodying the improvements. 60

Figure 2 is a view in section therethrough taken on the plane indicated by the line 2-2 of Figure 1 and looking in the direction of the arrows. 65

Figure 3 is a view in front elevation of the improved shingle showing the relation of the nailing strip thereto. 70

Figure 4 is a view in plan showing three rows of shingles of improved form laid in staggered relationship. 75

Figure 5 is a schematic view in side elevation showing the overlapping relation of successive rows of shingles. 80

Figure 6 is a fragmentary detail view in section showing the relation of the improved nailing strip to the tongue and groove joint whereby the surfaces of proximate shingles maintain the same plane. 85

The improved shingle *a* has formed therein a vertically extending channel *b* along its median line and a plurality of horizontally extending beads *c* adjacent its upper edge which assist in forming a weather-tight joint between successive rows of shingles as will appear from Figure 5. 90 Along one edge of the shingle is stamped and formed a tongue *a'* of preferably concave form while along the other edge is stamped and formed a groove *a''* by bending a section of the metal reversely on itself. At this edge is also provided the improved nailing strip *a''*. 95

In order to understand the improvements sought to be covered by the present application the method of laying the shingles must be considered. These shingles must be laid from left to right and the rows thereof from bottom to top, as viewed in the drawings. In practice, it is desirable that metal shingles when laid shall have the appearance of 100 wooden shingles and for this reason it is desirable to stagger them and so form them, as indicated in Figure 1, as to have the appearance of two shingles. This effect is secured by the vertical groove *b*. Heretofore, the problem has been to lay metal shingles in staggered relationship without necessitating the nailing through of two shingles and some disturbance of the smooth unbroken surface which should be presented 105 by juxtaposed shingles. In accordance with the present invention the nailing strip *a''* 110

is so formed as to provide a shoulder a^4 at a predetermined distance from the lower edge of the shingle this distance being determined by the desired amount of overhang 5 of the shingles in successive rows. In the illustrated embodiment, for instance, it is desirable that the vertical butt edge a^5 formed at the bottom of each shingle shall overlie the beads c, c , and to this end, the 10 shoulder a^4 on the nailing strip a^3 is so formed that when it abuts against the upper edge of the next lower shingle the butt edge a^5 will be automatically positioned in proper relation to such lower shingle. The parts 15 may be brought into this relation by a simple quick manipulation of the shingle by the workman and not only will the desired disposition be effected in this manner but the nailing strip a^3 will lie along the roof ready 20 for direct nailing without involving any of the other shingles. In this position the flat portion of the nailing strip rests on the sheathing along its entire length and provides a uniform and even support for the 25 shingle in its seated plane. As shown in Figure 4, for instance, nails may be driven through the holes a^6 in the nailing strip a^3 and the next shingle may have its tongue along its left edge engaged with the groove

at the right edge of the shingle a and so 30 forth for as many additional shingles and rows as are to be laid.

Changes in details of construction and relation of parts may be made by one skilled in the art without departing from the scope 35 of the invention as long as the advantages herein described are realized by equivalent mechanical means.

What I claim is:

A metal shingle having a lower butt edge 40 to raise the shingle from the plane of a lower shingle, a uniform upper butt edge perpendicular to the plane of the shingle to permit staggering of the shingles in any desired relation, a nailing strip inclined 45 downwardly from the plane of the raised shingle and having a flat portion along its entire length resting on the sheathing to support the side of the shingle evenly in such plane, a shoulder on the nailing strip 50 to rest against the upper butt edge of the lower shingle to space the respective shingles when in place, and a groove in the nailing strip to receive the edge of the adjacent shingle. 55

This specification signed this 14th day of February A. D. 1923.

GEORGE B. MEURER.
